United States Patent Office

Des. 192,615
Patented Apr. 17, 1962

192,615

LENS METER

John T. Armbruster, Niagara Falls, N.Y., assignor to
American Optical Company, Southbridge, Mass.

Filed Oct. 18, 1960, Ser. No. 62,518

Term of patent 14 years

(Cl. D57—1)

Fig. 4

Fig. 1

Fig. 3

Fig. 2

FIG. 1 is a side elevational view showing my new design;

FIG. 2 is a rear elevational view thereof;

FIG. 3 is a front elevational view thereof;

FIG. 4 is a fragmentary rear perspective view thereof, with the knobs omitted for convenience of illustration.

The side not illustrated is substantially the same as that shown in the drawing, and the dominant features of the design are shown in full lines.

I claim:

The ornamental design for a lens meter, substantially as shown and described.
